UNITED STATES PATENT OFFICE.

ELEUTHERE PAUL DU PONT, OF MONTCHANIN, DELAWARE.

INTERNAL-COMBUSTION ENGINE.

1,408,179.

Specification of Letters Patent. Patented Feb. 28, 1922.

Application filed February 25, 1919. Serial No. 279,083.

To all whom it may concern:

Be it known that I, ELEUTHERE PAUL DU PONT, a citizen of the United States, residing at Montchanin, county of New Castle, 5 and State of Delaware, have invented a new and useful Improvement in Internal-Combustion Engines, of which the following is a full, clear, and exact description, reference being had to the accompanying drawings, 10 which form a part of this specification.

My invention refers to internal combustion engines, used particularly in marine work, and has for its object the production of a casing or housing for such engines of a 15 special form and construction which first of all forms a complete enclosure for the engine and its auxiliary pumps and in addition, by the removal of a single unitary cover, admits of convenient access to all the mechanism 20 and provides for the ready removal of the crank shaft when desired and for the lubrication of the moving parts.

My invention comprises a single main casting horizontally disposed, of generally circular cross-section, with the front cut away 25 through the full length of the casting on a vertical plane cutting off a segment from the circular section. Upon the top of the main casting, which is flattened to receive them, 30 are mounted separately the cylinder casings and a hood for the pump mechanism. The open front of the main casting is closed by a single plate of appropriate form. A flanged head at one end of the main casting encloses 35 the fly wheel, while at the opposite end a flanged projection carries the thrust bearing for the shaft of the engine. The intermediate bearings for this shaft are provided for by webs in the main casing, and are arranged 40 at an angle of about 45° to provide for the ready removal of the shaft when the front cover plate has been taken off.

The main parts of the apparatus are thus seen to be few in number and of such shape 45 as to be readily machined and fitted to each other to form a complete housing for the engine. Furthermore, the pumps for the oiling system, water cooling and bilge draining are conveniently located in the casing and arranged so as to be operable from the main 50 shaft.

Having now stated in a general way the

character of my invention, as well as its principal object and advantages, I will proceed with a detailed description of an embodiment thereof, in connection with the accompanying drawings, in which—

Fig. 1 is a general view of the main castings, shown in perspective and separated from each other.

Fig. 2 is a vertical cross-section taken through one of the cylinders showing in general the main parts only.

Fig. 3 is a similar cross-section taken through the hood containing the pump 65 drives, etc.

The main casting *a*, forming the crank and gear casing, is of generally cylindrical form with the front sliced away longitudinally as shown in Fig. 1. The top of this casing is 70 flattened as at *b*, to which the cylinder castings *c*, *c* and the hood *d* are bolted.

Transverse webs in casing *a* carry bearings *e* for the crank shaft 20 between and on either side of the cylinders. These bearings 75 are arranged at an angle as stated and provided with removable caps for conveniently inserting and extracting the crank shaft.

The crank shaft is formed between bearings *e* with the usual integral cranks for 80 actuation from the cylinders and extends only a short distance at both ends beyond the end bearings. At its forward end the shaft carries a fly wheel, not shown, located in the circular open end of the main casing and arranged to be entirely enclosed by the circular 85 end cover *f*.

At the opposite end the casing forms a compartment *g* between its end wall and the after bearing *e* in which is located the reverse gearing, etc. At this end the crank shaft is provided with a flanged coupling (not shown) right next to the bearing, and by this coupling connects with an extension which operates the reverse gears and passes 90 on out the rear of the compartment where it is supported in bearings in a bonnet *h* arranged to be bolted to the end of casing *a*.

The entire open front of the casing is flanged and arranged to be closed by a single front plate *i*. The cylinder castings *c*, *c* have open front compartments for containing the valve operating cams *j*, and also carry the bearings *k* for the cam shaft. These com-

partments are flanged in alinement with the flange on the front of casing *a* so that they are also closed by front plate *i* which is provided with projections *l* for covering these compartments.

The crank compartments in casing *a* between bearing *e* are each provided at the back with an air inlet *m* as shown in Figure 2. As shown in this figure, the valve operating mechanism is indicated at *n*, and it is completely enclosed at the top by a light casing *o*. From this casing a pipe *p* leads to the suction of the vaporizer *q* and thence to the inlet passage *r* in the cylinder head.

The operation is as follows: The cranks *s* dip into a bath of oil in the bottom of the casing, and in their rapid rotation churn the oil into a mist or spray which permeates the whole interior of the casing and cylinders. Air enters the inlets *m* and passing through the casing becomes laden with particles of oil due to the splash action of the cranks, and carries them up about the valve operating mechanism, as indicated by the arrows in Figure 2, and thence passes through pipe *p* to the carbureter. By this time it has lost practically all of its oil particles, which have been deposited on the moving parts in its path, thereby insuring their thorough lubrication.

Thus a continuous, yet rather slow, circulation of air is provided from the inlets, through the crank compartments, where it gets heated, to the mixing chamber of the carbureter, on its way lubricating the cams and valve mechanism.

The end compartment *g* carries gearing *t* for operating the cam shaft *u*,—see Figure 3. On the shaft of one of these gears is conveniently mounted an eccentric *v* for actuating the rocker *w* for operating the pumps *x*, *y* and *z*; *x* representing the air pump for supplying air under pressure to a suitable reservoir to which a whistle pipe may be connected, *y* the pump for supplying water to the cooling jackets, and *z* a pump for removing the bilge water.

As will be seen in the drawing, the front plate *i*, where it covers this portion of the casing, is dished out and carries pumps *y* and *z* on its face, operable by a single plunger *g* which is actuated by the slotted end of arm 6 of rocker *w*. The air pump *x* is operated by a link 7 connected with another arm of rocker *w*.

Rocker *w* also operates the oil pump 8 in the following manner: At this point the casing is cut out at the bottom, as shown at 9, and the dished portion of the front plate *i* is extended down to meet it and form therein an oil pocket or well 10. Into this pocket extends oil pump 8 which is mounted to slide on a fixed plunger 11 comprising a pipe carrying at its lower end inlet valve 12 and at its upper end connecting with the sight feed

arrangement 13, from which a tube 14 provides lubrication for the gearing *t* and other mechanism in hood *d* and another tube 15 leads to the forward end of the engine, where oil overflows various divisions in the crank case, finally returning to the bath in the bottom of the casing. Pump 8 carries an inlet valve 16 at its lower end and is operated to raise and lower upon pipe 11 by means of a pin 17 on rocker *w*, being held thereon by a spring 18 abutting against a collar on the pipe. The action of the pump is as follows: As the rocker is turned to lower pin 17, spring 18 forces pump 8 down into the oil in well 10, and oil enters inlet valve 16. Upon the upstroke of the rocker, pin 17 raises the pump and the oil contained in its lower end is forced through valve 12 into pipe 11. As this is a continuous process, a certain quantity of oil is kept circulating through pipes 14, 15, as can be ascertained by the sight feed 13.

The advantages of this arrangement are that a great deal is accomplished by a very few parts. A single eccentric operates the four pumps, the lubrication of every moving part is provided from a single oil delivery pipe, and complete accessibility is afforded to each pump without disturbing any other working part.

Enclosing the fly wheel with the rest of this engine is a great advantage besides merely protecting a moving part. Otherwise an irregular piece would have to be fitted in above the cap of end bearing *e* to prevent oil from splashing out. This is always difficult to keep tight and at the same time allow for adjustment of the bearing cap. By inclosing the fly wheel this trouble is obviated.

It is also common practice to place the cam shaft bearings in the crank case proper where the latter is open at the side. This prevents ready access to the inside parts, which is obviated by my arrangement.

By virtue of the flange coupling in the crank shaft it will be seen how readily the shaft may be disconnected and removed, by first removing the front plate *I* and then taking off the caps of the bearings *e*. A further advantage of the arrangement is that all the accessories and points needing attention or adjustment are located on one side, so that in marine practice a partition can be placed against the other side without in any manner interfering with the convenience of attending to the running of the engine and the various adjustments.

Casing *a* may be provided with feet 19, integral therewith, as indicated in Figure 2, for supporting the entire engine upon suitable foundations.

I do not herein claim certain novel features, relating more especially to the lubricating system, herein set forth, as the same

forms the subject-matter of a divisional application filed September 11, 1919, Serial No. 323,181.

Having now fully described my invention, 5 what I claim and desire to protect by Letters Patent is:

1. In an internal combustion engine, the combination with a casing for the crank shaft and gearing, opening along its front 10 and at one end, of a removable front plate closing the front opening, and a removable end cover engaging both the casing and the front plate.

2. In an internal combustion engine, the 15 combination with a casing for the crank shaft and gearing, opening along its front and at one end, the front opening extending to said open end, a removable front plate, closing the front opening, and a removable end cover plate, the front ends of the casing 20 and cover having together a rim to which the end cover is adapted to be secured.

3. In an internal combustion engine, the 25 combination with a casing for the crank shaft and gearing opening along its front, of a removable front plate closing said front opening, one end of the casing and the corresponding end of the front plate having unitedly a circular contour, and a removable 30 end cover of dished circular contour adapted to fit the flanged end of the casing and front plate and adapted to form a fly wheel enclosure.

4. In an internal combustion engine, the 35 combination with a casing for the crank shaft and gearing having a continuous opening along its front to afford access to its interior and having also an end opening, a single removable front cover plate closing 40 said front opening, and a removable end cover plate covering said end opening.

5. In an internal combustion engine, the 45 combination with a casing for the crank shaft and gearing, opening along its front and provided with openings in its top, of cylinder castings open in front and mounted on the casing over said openings, and a removable front plate shaped to close said casting and provided with integral upstanding 50 wings adapted to close the cylinder castings.

6. In an internal combustion engine, the 55 combination with a main casing for the crank shaft and gearing opening along its front and provided with a deep opening in its top, an auxiliary casing mounted on the main casing and having a bottom opening registering with the opening in the top of the casing and a front opening, and a front plate adapted to close the front of the main 60 casing and shaped opposite the auxiliary casing to form an enclosure opening toward the auxiliary casing and forming with it a chamber adapted to enclose certain of the working parts.

65 7. In an internal combustion engine, the

combination with the cylinders and moving parts thereof including the crank shaft, of an open faced housing for enclosing the moving parts, a cover for the opening in said housing, two pumps mounted on said cover, 70 a common plunger for said pumps, an eccentric on the shaft, a rocker actuated by said eccentric, and driving connection between the plunger and the rocker.

8. In an internal combustion engine, the 75 combination with the cylinders, the carbureter and moving parts; including the valve actuating mechanism and crank shaft, of a housing, means in the housing providing an oil bath, an air inlet in the housing, and 80 means to lead the incoming air circuitously through the housing, about the moving parts therein to pick up oil thrown by the crank shaft and deposit it on the valve actuating mechanism in its passage from the oil bath 85 to the carbureter of the engine.

9. In an internal combustion engine, the combination with a crank case adapted to support the cylinders and provided with a continuous opening throughout one side, of 90 bearings in the case to support the crank shaft, transverse webs extending about the interior wall of the case and acting to support the bearings, a crank shaft adapted to be removed bodily through said opening in 95 the case and a closure for said opening.

10. In an internal combustion engine, the combination with a case for the crank shaft and gearing opening along its front and provided at its top with openings for the engine 100 cylinder and a deep indentation, cylinder castings and a gearing enclosing a hood also opening along its front forming a continuation of the open front in the casing mounted upon the case and communicating with the 105 case through said openings and deep indentation respectively, shaft bearings in the case, webs supporting said bearings and functioning also as braces, and a removable cover plate for the open front. 110

11. An engine frame comprising a combined crank casing having seating surfaces at an angle to each other, a cylinder casting having similar seating surfaces, one of the seating surfaces of the cylinder casting being 115 arranged to be seated on one of the seating surfaces on the crank casing, while the other seating surface on the cylinder casting forms a continuation of the other seating surface of the crank casing, and a cover plate connected to the last mentioned seating surfaces. 120

12. An engine frame comprising a combined crank casing having seating surfaces at an angle to each other, a cylinder casting 125 having similar seating surfaces, one of the seating surfaces of the cylinder casting being arranged to be seated on one of the seating surfaces on the crank casing, while the other seating surface on the cylinder casting 130

forms a continuation of the other seating surface of the crank casing, a cover plate connected to the last mentioned seating surfaces, an annular flange formed on one end 5 of the crank casing and the cover plate, and a fly-wheel casing secured to said flange.

13. An engine having a crank casing, reinforcing webs in said casing, a crank shaft journaled in bearings on said webs, said casting having a horizontal and a vertical seating surface, a cylinder casting secured to the horizontal seating surface, cam shaft bearings in the cylinder casting at one side thereof, a cam shaft, valve actuating cams there-

on, a vertical seating surface on the cylinder 15 casting forming an elongation of the vertical seating surface on the crank casing, there being a recess formed in the cylinder casting for the valve actuating mechanism and the cams therefor, and a cover plate secured to 20 the elongated seating surface on the crank casing and the cylinder casting to form a closure for the mechanism in the crank casting and the recess in the cylinder casting.

In testimony of which invention, I have 25 hereunto set my hand, at Wilmington, on this 5th day of February, 1919.

ELEUTHERE PAUL DU PONT.
